UNITED STATES PATENT OFFICE.

WILLIAM S. ARCHER, OF PROVIDENCE, RHODE ISLAND.

MACHINE FOR DISINTEGRATING, CLEANING, AND ASSORTING FIBROUS MATERIALS.

No. 810,898.

Specification of Letters Patent.

Patented Jan. 30, 1906.

Application filed October 5, 1904. Serial No. 227,277.

To all whom it may concern:

Be it known that I, WILLIAM S. ARCHER, a citizen of the United States, residing at Providence, in the county of Providence and State 5 of Rhode Island, have invented certain new and useful Improvements in Machines for Disintegrating, Cleaning, and Assorting Fibrous Materials, of which the following is a specification, reference being had therein to the accompanying drawings.

My invention relates to that class of machines for cleaning and disintegrating fibers wherein the foreign or extraneous matters are eliminated by the use of grid and similar 15 toothed bars, and has for its object a mechanism which is adapted to clean or disintegrate a variety of fibers, either vegetable, animal, or mineral, with a minimum of adjustment, to segregate into their respective classes the 20 by-products or refuse resulting from the cleansing operation, and to attain with increased speed and efficacy at a minimum cost the ends commonly sought in this class of mechanisms.

Other advantages will later appear in the description and be claimed.

In the accompanying drawings, which form a part of this specification, Figure 1 is a longitudinal central section of the novel mechanism; Fig. 2, a plan view of one of the bars, and Fig. 3 an end elevation of same.

Like reference-numerals indicate like parts throughout the views.

A convenient structure for embodying the invention comprises a substantially air-tight casing or frame 1, in the forward portion of which is mounted rolls 2 for driving a horizontally-disposed apron 4, upon which the asbestos or other fiber to be cleaned or disintegrated is originally placed. Adjacent the inner extremity are mounted a pair of feed-rollers 5, through which the fiber is fed toward the lower surface of a picker-roller 6, also mounted on a revoluble shaft 7 in the 35 casing and which coats with the double teeth of a plurality of cleaning-bars 8 to perform the first cleaning or disintegrating step. The latter are fixedly mounted in the sides of the casing. A deflecting-plate 3 is fixed to the 40 casing in the rear of the picker-roller. Horizontal channels 10 traverse the inner sides of the casing, in which are adjustably supported the ends 11 of a series of cleaning-bars 12, 13,

and 14. The bars, (shown in detail in Figs. 2 and 3,) with their longitudinally-disposed 55 teeth series 15, are arranged as follows:

The bars 12 nearer the picker-roll are inclined rearwardly, so that the upper or knife edge is slightly disposed in a direction opposite the travel of the fibers. The next or central series of bars 13 are mounted exactly perpendicular, and one of the series has depending from its lower edge a rectangular strip 16, which serves as a transverse wall in the casing. The third or final bar series 14 are inclined 65 toward the direction of travel of the fiber, and to the first of these bars is fixed a strip 17, furnishing a second transverse wall in the casing and forming with strip 16 three compartments 18, 19, and 20.

In the rear end of the casing adjacent the bars 14, but separated from the latter by a partition 21, is a circular cage 22, whose body is preferably formed of a wire mesh and which is mounted upon a perforated hollow 75 shaft 23, journaled in the casing. At a distance above the cage 22 is mounted in the casing a second cage 24, similarly constructed and mounted upon a hollow perforated shaft 25. These cages are rotated in opposite directions 80 from any convenient source of power. Mounted in the casing contiguous to the cages 22 and 24, respectively, are rollers 26 and 27 with rough surfaces, which both serve to strip any adhering fiber from the cages and at the 85 same time facilitates the delivery of the fiber through the opening 28 in the rear of the casing.

A blow or dust pipe 29 leads from the outer end of the hollow shaft 25 to a blower 30 outside the casing, and a branch blow or dust pipe 31 leads from pipe 29 to the outer end 90 of the hollow shaft 23.

The operation of my machine is as follows: The fiber to be treated is fed by the apron 4 and rolls 5 into the casing intermediate the picker-roll 6 and the double-toothed bars 8, 95 where the interaction of the picker and bar-teeth assist the segregation of the heaviest refuse, which is carried down between the 100 bars by gravitation. The deflector-plate 2' deflects stones and heavy matter intermediate the bars below. Continuously from its first entrance into the casing the fiber is subjected to the strong suction in a horizontal direction 105 of the blower 30 acting through pipes 29 and

31, which causes the long fiber to travel over the toothed upper edges of the various bar series 12, 13, and 14 successively. The varying nature and condition of different fibers demands at times a change of intensity in the air-current. This is attained by varying the speed of the blower. The fibrous material in its passage over the bars 12 discards its heavy refuse downwardly intermediate the latter into compartment 18. Proceeding, the fiber passes over the bars 13, which have a less positive or harsh effect upon the fiber already partially cleansed, and deposits its waste matter and short fiber in compartment 19. Continuing, the fiber passes over the bars 14, where the obtusely-inclined position of the bars is adapted to disintegrate the lighter adhesions, such as leaves in cotton, and the enlarged interstices permit the same to descend into the bin or compartment 20. The relative angles at which the different series of bars are set may be varied to advantage for cleansing or disintegrating different materials. The passage of asbestos through the machine results in a deposit of relatively uniform lengths of the shorter fibers in each of the receptacles 18 and 19, while the needles are deposited in receptacle 20. After traversing the bar series, as above described, the fiber is forced intermediate and against the cages 22 24, and the dust is drawn therefrom through the perforated shafts 23 25 and their respective pipes 31 and 29. It will be observed that the suction of the blower not only conveys the residual material across the machine and is an auxiliary in the disintegrating operations, but also cleanses the material from dust. The control of the traveling fiber is augmented by the fact that the partitions 16, 17, and 21 are comparatively air-tight. The fibers after traveling between cages 22 and 24 are delivered from the casing by the rolls 26 and 27. The latter also strip any adhering fiber from the peripheries of the cages.

Having described my invention, what I claim is—

1. In a machine of the class described, the combination with the feeding and delivery mechanism, of a plurality of bars intermediate the feeding and delivery mechanism and suction means acting in a horizontal direction on the fiber from its introduction into the machine, for conveying the material fed over the bars, and separated receptacles beneath said bars and in connection with which said bars are differently spaced.

2. In a machine of the class described, the combination with the feeding and delivery mechanism, of a plurality of toothed bars intermediate the feeding and delivery mechanism, and suction means acting in a horizontal direction on the fiber from its introduction into the machine for conveying the material

fed over the bars, and separated receptacles beneath said bars and in connection with which said bars are differently spaced.

3. In a machine of the class described, the combination with the feeding and delivery mechanism, of a plurality of toothed-bar series intermediate said mechanism, the bars of each series as their distances from the picker-roller increases being inclined at a different vertical angle from the bars of the other series, and separated receptacles beneath said bars and in connection with which said bars are differently spaced.

4. In a machine of the class described, the combination with the feeding and delivery mechanism, of toothed-bar series intermediate said mechanisms, one series being vertical and the other two series being inclined in relation to the vertical series, and separated receptacles beneath said bars and in connection with which said bars are differently spaced.

5. In a machine of the class described, the combination with the feeding and delivery mechanism, of a plurality of toothed-bar series intermediate said mechanism, the bars of each series being interspaced differently from the bars in the other series, and separated receptacles beneath said bars and in connection with which said bars are differently spaced.

6. In a machine of the class described, the combination with the feeding and delivery mechanism, of a series of inclined toothed bars rear the feeding mechanism, a second series of toothed bars next the first bar series vertically positioned and wider spaced, and a third series of toothed bars oppositely inclined to the inclination of the first series and spaced wider than the second series and mounted next the second bar series, said series being arranged at different distances from the picker-roller, and separated receptacles beneath said bars and in connection with which said bars are differently spaced.

7. In a machine of the class described, the combination with the feeding and delivery mechanism, of a plurality of toothed-bar series intermediate said mechanism, said series being disposed at different distances from the picker-roller, the bars of each series being inclined at a different vertical angle from the bars of the other series, and suction means for forcing the material fed across the bars, and separated receptacles beneath said bars and in connection with which said bars are differently spaced.

8. In a machine of the class described, the combination with the feeding and delivery mechanism, of a plurality of toothed-bar series intermediate said mechanisms, and disposed at gradually-increasing distances from the picker-roller the bars of each series being interspaced differently from the bars in the other series, and suction means for forcing the materials fed across the bars and separated re-

- ceptacles beneath said bars and in connection with which said bars are differently spaced.
9. In a machine of the class described, the combination with the feeding and delivery mechanism, of an oblong casing intermediate said mechanisms, a plurality of toothed bars mounted transversely in the casing, and strips depending from the bars to form adjacent receptacles.
10. In a machine of the class described, the combination with the feeding and delivery mechanism, of a plurality of toothed bars intermediate the feeding and delivery mechanism, a meshed surface adjacent the toothed bars, and suction means acting in a horizontal direction on the fiber from its introduction into the machine for forcing the material fed against the meshed surface and separated receptacles beneath said bars and in connection with which said bars are differently spaced.
11. In a machine of the class described, the combination with a horizontal series of toothed bars of a meshed surface adjacent the toothed bars and suction means acting in a horizontal direction on the fiber from its introduction into the machine for conveying the materials over the bars and forcing said materials against the meshed surface and separated receptacles beneath said bars and in connection with which said bars are differently spaced.
12. In a machine of the class described, the combination with a series of toothed bars of a

revoluble cage adjacent the toothed bars, a perforated hollow shaft upon which the cage is mounted, a blower, and a pipe connecting the blower and shaft.

13. In a machine of the class described, the combination with a series of toothed bars and separated receptacles beneath said bars and in connection with which said bars are differently spaced of a revoluble cylindrical cage adjacent the bars, suction means acting in a horizontal direction on the fiber from its introduction into the machine for forcing the materials over the bars and against the cage, and a roll adjacent the cage adapted to strip the material from the cage periphery.

14. In a machine of the class described, the combination with a series of toothed bars and separated receptacles beneath said bars and in connection with which said bars are differently spaced of revoluble cylindrical cages adjacent the bars, suction means acting in a horizontal direction on the fiber from its introduction into the machine for conveying materials over the bars and intermediate the cages, and a roll adjacent each cage for delivering the materials.

In testimony whereof I have affixed my signature in presence of two witnesses.

WILLIAM S. ARCHER.
